UNITED STATES PATENT OFFICE.

JOSEPH B. STRAUSS, OF CHICAGO, ILLINOIS.

BRIDGE AND PROCESS OF MAKING THE SAME.

No. 811,257.

Specification of Letters Patent.

Patented Jan. 30, 1906.

Application filed December 10, 1904. Serial No. 236,408.

To all whom it may concern:

Be it known that I, JOSEPH B. STRAUSS, a citizen of the United States, residing at Chicago, in the county of Cook and State of Illinois, have invented a certain new and useful Improvement in Bridges and Processes of Making the Same, of which the following is a specification.

My invention relates to improvements in concrete or concrete-steel bridges and the process of making the same, and has for its object to provide a new and improved construction and process of this description.

My invention is illustrated in the accompanying drawings, wherein—

Figure 1 is a plan view of a bridge embodying my invention with the floor removed and before completion. Fig. 2 is a side elevation of a bridge embodying my invention when completed and with the floor in position. Fig. 3 is a sectional view taken on line 3-3 of Fig. 1 before the hollow sections are filled in. Fig. 4 is a sectional view taken on line 4-4 of Fig. 1 after the hollow sections are filled in. Fig. 5 is a side elevation of two of the hollow sections with parts broken away, showing the method of construction and connection. Fig. 6 is an enlarged plan view showing the method of connecting the ribs of the bridge with the cross-pieces or diaphragms. Fig. 7 is a plan view of a part of the bridge, showing one form of floor before the floor is completed. Fig. 8 is an enlarged sectional view on line 8-8 of Fig. 7 after the floor is completed.

Like letters refer to like parts throughout the several figures.

One of the objects of my present invention is to provide a concrete or concrete-steel bridge which can be made in sections in the shop and then transferred to the place where the bridge is to be assembled and there placed in position. As shown in Fig. 1, which illustrates the bridge before completion, such bridge consists of a series of ribs A A', preferably extending the length of the bridge and connected by cross-pieces or diaphragms C. Each of the ribs is made up of sections A² A³ A⁴, &c., adapted to be made up separately and assembled. The strengthening cross-pieces or diaphragms C are also made separately and placed in position. The sections of the ribs and the diaphragms C are preferably made up in hollow shell-like pieces and are then assembled to form the outline of the bridge and are then filled in to form the complete structure. These sections may be

formed in any desired manner. As illustrated in Figs. 3, 5, and 6, each section is provided at the top with the reinforcing or supporting bars or pieces D, which are separated 60 the proper distance to secure the proper width of the rib. A series of wires or looped connecting-pieces D' are attached to the supporting-pieces D and are formed into loops of such length, as shown in Figs. 3, 4, and 5, 65 as to secure the desired height of rib. These connecting-pieces may be attached to the supporting-pieces in any desired manner, and, as shown in Fig. 4, they are simply hooked over such supporting-pieces. The 70 loops are preferably connected together at the bottom in some desired manner, as by means of the pieces D², which may be attached thereto by wires or in any other manner, so as to keep the connecting-pieces 75 properly spaced while the concrete is being applied thereto. The parts thus connected form a frame, and then concrete or cement or the like is applied to this frame, so as to form comparatively thin walls and provide a 80 hollow shell or section. The outside of these sections is preferably made smooth and the inside rough—as shown, for example, in Fig. 3.

The diaphragms or cross-pieces C are made in substantially the same manner. I prefer, 85 however, to connect the supporting-pieces D of these cross-pieces or diaphragms across the ends thereof, as shown at E, so as to form means for connecting the diaphragms to the ribs. In these diaphragms there may be a 90 single supporting-piece D, and it may extend entirely around the diaphragm, so as to form a parallelogram. The sections of the ribs and the diaphragms are made up in the shops and the ends of the supporting-pieces D are 95 left exposed. I prefer also to provide these sections at intervals with rods or bolts F, which pass through engaging pieces F', such rods or bolts being surrounded by separators F², thus holding the sections in proper shape. 100 When the sections are to be assembled, they are placed in proper relation to each other and are connected in position. A convenient means for doing this is to permit the ends of the supporting-pieces D to overlap, 105 as shown in Figs. 5 and 6, and to then provide bolts G, which pass through these supporting-pieces and through the end pieces E of the cross-pieces or diaphragms C, such bolts extending through both ribs and entirely 110 across the bridge, as shown in Figs. 1 and 6. These bolts are also preferably provided with

sleeves G' , which act as separators. The sections are preferably provided at the bottom with fastening-pieces D^4 , which are embedded in the cement walls and which project therefrom, as shown in Fig. 5, and overlap. A bolt G^2 passes through these ends and through the diaphragm C . This bolt is similar to the bolt G and has the spacing or separating sleeves upon it. The fastening-pieces D^4 are preferably connected at their ends to the connecting-pieces D^2 . The fastening-pieces D^4 are left at their ends free from cement in a manner similar to that described in relation to the supporting-pieces D .

15 The diaphragms C are provided at the bottom with holding-pieces D^5 , (see Fig. 3,) which extend entirely across the end of the diaphragm and are bent around on the sides and embedded in the walls, the ends being connected with connecting-pieces D^2 , similar to those used in the sections of the ribs. The end pieces E are preferably bent at the point of connection, so as to be brought into proximity to the supporting-pieces D to act as 25 separators and to hold the parts in their proper relation. I also prefer to provide a series of anchor-bolts H , which pass through the walls of the ribs and project into the interior thereof and into the interior of the 30 cross-pieces of the diaphragm C , as shown in Figs. 3 and 6.

The diaphragms or cross-pieces are preferably connected with the ribs opposite the point where two sections of the ribs are 35 united. After the diaphragms and hollow sections are in position they are properly aligned and the joints filled with cement or the like, the exposed ends of the supporting-pieces being also covered, so as to make a 40 smooth exterior surface. The sections are then filled in with concrete and iron or the like and the material left to dry. In filling in these sections steel "T's" I (see Fig. 4) or other iron may be used in any desired quantities and of any desired size or shape.

45 It will be seen that when the material dries and hardens there will be formed a solid concrete or concrete-steel construction. The floor J may then be placed in position and 50 may itself be of concrete or concrete-steel or of any other material.

It will be seen that by means of this construction I am enabled to form a concrete bridge which may be made up in light sections, so that the bridge may be erected, as it were, in outline and subsequently filled in with steel and bulk concrete, permitting the sections to be erected singly and permitting the work to progress from one or both supports.

55 It will further be seen that this arrangement greatly cheapens the construction and does away with the expensive forms and false work now required in making concrete

bridges. Whatever facing is to be done can 65 be done in the shop by properly facing the outer surface of the sections, and hence no facing is required in constructing the bridge. The shells may be made in any suitable shop and shipped to the locality where the bridge 70 is to be erected.

It will be seen that instead of having the expensive false work the parts which hold the concrete in shape while drying become a permanent part of the bridge.

75 Any cracks which may develop in the concrete will not appear on the surface under these conditions.

It will be seen that the sections have communication with each other at their ends, so 80 that the concrete when filled in forms, as it were, a continuous core which passes from one section to the other, so as to unite them in solid structure. Each of the ribs of this device, therefore, forms a horizontal girder 85 supported at the end and free between the ends, the solid core uniting with the cement shell-like sections so as to constitute a solid structure.

It is also evident that this construction 90 may be applied to piers and all other forms of concrete or concrete-steel construction. In the claims I have used the term "concrete," and I use this term broadly to cover any construction where concrete or concrete-steel or 95 cement or the like is used.

I have described in detail a particular construction by means of which the sections are formed; but it is of course evident that this construction may be varied in many particulars, and I therefore do not limit myself to the particular construction, form, and arrangement shown.

In Figs. 7 and 8 I have shown one manner of forming the floor, although, as before 105 stated, any form of floor may be used. In these figures I provide a series of floor-pieces K , preferably made of concrete or the like. As shown in these figures, such floor-pieces are provided with rigid pieces of steel or the like, K' , embedded in the concrete. The ends of the floor-pieces are bent, as shown in Fig. 8, so as to hook over the sides of the hollow sections of the ribs. In forming the floor the floor-pieces are placed in position and slightly 110 separated, the space above the diaphragms or cross-pieces C being left open, as shown in Fig. 7. The concrete or the like is then filled in, so as to cover the floor-pieces, thus making the floor integral with the filling in the 115 ribs and cross-pieces.

If desired, pieces of steel or the like K^2 may be embedded in the floor, as shown in Fig. 8. These steel pieces may run in either direction or in both directions, if desired. The material will also pass in between the floor-pieces, so as to firmly bind them together. When 120 this form of floor is used, the outer edges of

the hollow sections of the ribs are made longer than the inner edges, as shown in Fig. 8, so as to hold the floor material in position while drying and form a proper facing therefor. In these figures I have shown two ribs for purposes of illustration; but it is of course evident that the number of ribs may be multiplied to meet the conditions presented.

I claim—

10 1. A concrete horizontal girder comprising a series of shell-like sections placed end to end and communicating with each other, said sections having concrete walls and a solid concrete core extending from one section to the other and binding them together into a rigid self-supporting structure.

15 2. A concrete bridge comprising a series of separated concrete ribs formed in sections and connected together, and a series of concrete lateral diaphragms separately made and fastened in position between said ribs.

20 3. A concrete structure comprising a series of separated concrete ribs formed in sections and connected together, and a series of concrete lateral diaphragms separately made and fastened in position between said ribs, said concrete lateral diaphragms fastened to the ribs at the points where the sections of the ribs are united.

25 30 4. A building-section comprising separated supporting-pieces, a series of looped connecting-pieces attached thereto at intervals, a concrete facing supported upon said supporting and connecting pieces so as to form a hollow shell-like section, the ends of the supporting-pieces left free from cement.

35 40 5. The combination in a bridge of a series of sections made up of separated supporting-pieces and looped connections embedded in concrete so as to form shell-like sections and connected together in proper relation so as to form the outline of the structure, adapted when filled in to form a solid unitary construction.

45 50 6. The combination in a bridge of a series of ribs made up of sections each consisting of separated supporting-pieces and looped connections embedded in concrete so as to form shell-like sections and connected together in proper relation so as to form continuous ribs, and a series of cross-pieces or diaphragms connected to said ribs at intervals.

55 60 7. The combination in a bridge of a series of ribs made up of sections each consisting of separated supporting-pieces and looped connections embedded in concrete so as to form shell-like sections and connected together in proper relation so as to form continuous ribs, and a series of cross-pieces or diaphragms connected to said ribs at the points where the sections of the ribs are united.

65 68 8. The combination in a bridge of a series of ribs made up of sections each consisting of separated supporting-pieces and looped con-

nections embedded in concrete so as to form shell-like sections and connected together in proper relation so as to form continuous ribs, a series of cross-pieces or diaphragms connected to said ribs at the points where the sections of the ribs are united, and a connecting-piece extending through the ribs and the intermediate connecting-piece or diaphragm.

70 75 9. A building-section comprising a frame, a concrete facing supported upon said frame so as to form a hollow shell-like section, and overlapping connecting devices at the ends thereof for connecting said section in position in the structure and a uniting-piece passing through said overlapping devices so as to unite them.

80 85 10. A bridge comprising a series of shell-like concrete sections fastened together so as to form separated ribs and lateral braces, and a solid uniting-core in the sections forming the ribs and running from one to the other so as to form solid ribs.

90 95 11. A bridge comprising a series of separated longitudinal ribs, a series of transverse ribs to act as cross-bracing, the two sets of ribs formed of a series of shell-like sections having concrete walls and fastened together, the sections of the longitudinal and transverse ribs provided with concrete filling which forms an integral construction extending longitudinally and transversely so as to unite the sections and form a solid rib construction.

100 105 12. A building-section comprising a rigid frame consisting of longitudinal and transverse pieces embedded in concrete and forming a hollow shell-like section, and intermediate connecting-pieces extending through the hollow of the section and fastened to the transverse pieces in the opposed walls thereof, said section adapted to be filled in after being placed in position so as to form a solid structure.

110 13. A concrete bridge comprising a series of shell-like ribs, a series of floor-pieces spanning the space between the adjacent edges of said ribs, said ribs filled with concrete which extends over the floor-pieces so as to form a floor integral with the filling in the ribs.

115 14. A concrete bridge comprising a series of shell-like ribs and cross-pieces, a series of floor-pieces spanning the space between the adjacent edges of said ribs, said ribs and cross-pieces filled with concrete which extends over the floor-pieces so as to form a floor integral with the filling in the ribs and cross-pieces.

120 125 15. The process of forming structures which consists in forming a series of hollow sections having a rigid frame embedded in concrete walls, then assembling said sections to form a series of shell-like ribs and cross-pieces, then supporting a series of floor-pieces on the inner edges of said ribs, and then filling in the

ribs and covering the floor-pieces with concrete so as to form a floor integral with the filling in the ribs.

16. A concrete bridge comprising a series of concrete ribs and cross-pieces, and a series of concrete floor-pieces separate from the ribs and spanning the space between the ribs,

and means for holding said floor-pieces in position.
